VARIABLE CONDENSER CONSTRUCTION

Alexandre Horowitz, Eindhoven, Netherlands, assignor, by mesne assignments, to Radio Corporation of America, New York, N. Y., a corporation of Delaware

Application June 9, 1938, Serial No. 212,693
In the Netherlands July 16, 1937

2 Claims. (Cl. 74—459)

As regards to rotary shafts present in electric apparatus it is frequently desirable that they should be journalled in the apparatus so as to have practically no play and, besides, to be self-centering. Such is particularly the case if such shafts actuate members with which a slight displacement of the shaft highly affects the qualities of the apparatus and consequently any amount of play or any displacement of the shaft from its central position may have a harmful effect on said qualities. If, for example, the member actuated by the shaft is formed by one of the halves of a variable condenser, it will be evident that any possibility of play of the shaft or a permanent displacement of the latter from its normal position results in an undesirable uncontrollable alteration of the capacity of the condenser. According to the invention, these drawbacks are avoided.

The invention relates to an electric apparatus such as a radio-receiving apparatus wherein one or more of the rotary shafts present in the apparatus are journalled so as to have substantially no play and, besides, to be self-centering in a ball bearing whose balls run in a path which is formed by a couple of conical contact surfaces on the shaft in question and by a couple of similar contact surfaces in the stationary portion of the bearing, one of the latter contact surfaces being slightly movable with respect to the other contact surfaces and being forced by resiliency against the balls.

The electric apparatus may be of very different character. In addition to radio receiving apparatus there may also be considered, for example, measuring tables, in general that group of apparatus wherein for some reason or other it is desirable that the rotary shafts should be journalled without any play and be automatically centered.

Concerning the action of the playless, self-centering bearing according to the invention the following may be observed. In the assumption that the shaft considered is not removed from its central position by a non-excessive load, the return of this shaft into its original position, after an axial overload, due to which the shaft has consequently been removed from its central position, has ceased, has to be imagined to take place in such manner that, after the overload has ceased, this shaft is restored to its original position due to the co-operation of the movable contact surface, the balls and the contact surface in the shaft, which is located diametrically opposite the movable surface and to the fact that

the movable surface is pressed by resiliency against the balls. Besides, the points of contact of the balls with one of the contact surfaces will always be located on a conic section which is determined by the cutting of the contact surface under consideration by the plane which comprises the points of contact of the balls. The position of equilibrium of the balls is attained when the conic section assumes the shape of a circle. The balls always tend to occupy this position of equilibrium. If the shaft is radially overloaded, due to which the shaft consequently makes an angle with the centre-line of the shaft in its normal position, the points of the balls which are in contact with one of the contact surfaces will come to lie on a conic section different from the circle of equilibrium for example on an ellipse. When the radial overload ceases to exist the balls will occupy again their position of equilibrium. In this case the points of the balls which are in contact with one of the contact surfaces come to lie again on a circle, with the result that the shaft occupies again its original central position in the bearing. The above-described construction permits to manufacture a cheap, self-centering bearing which is practically without any play, from components which need no particular further treatment, such in contradistinction to the ball-bearings which, in order to have at the utmost a clearance of a few thousandths of a millimetre, require a very careful further treatment, in the present case regrinding of the contact surfaces, which entails of course considerable costs.

The apparatus according to the invention may have a bearing whose movable contact surface is secured, through the intermediary of one or more resilient washers, to the fixed portion of the bearing. These washers ensure in this case that the balls are forced by resiliency against the contact surfaces. According to the invention, this effect may also be obtained by making the movable contact surface itself somewhat resilient and, if desired, by securing such a resilient contact surface to the bearing also through the intermediary of one or more resilient washers.

The contact surfaces are preferably so formed that their generating lines makes angles of from 30 to 60° with the centre-line of the shaft journalled in the bearing when it occupies its central position. It is advisable that the angles formed by these lines pertaining to the contact surfaces in the fixed portion of the bearing or to the shaft are two by two mutually equal, slip of

the balls with respect to the contact surfaces being thus avoided.

The number of balls utilised in the bearing may in general be chosen at will. If the load on the shaft is not too large, it is advisable, in accordance with the invention, to journal the shaft on three balls owing to which a statically determined journaling of the shaft is obtained. These balls are preferably kept spaced apart by a ball race. The shaft journalled in the bearing may of course be hollow or solid.

The journaling above described is particularly advantageous for supporting a variable condenser present in the apparatus according to the invention, which may be formed, for example, either as a rotatable or as a slideable condenser.

The invention will be explained more fully with reference to the accompanying drawing wherein

Figure 1 represents a cross-section of a slideable condenser present in the apparatus according to the invention. Fig. 2 is a plan view of Fig. 1. Fig. 3 is a cross-sectional view, on an enlarged scale, of the bearing at the operating end of the condenser frame. Fig. 4 is a cross-sectional view, on an enlarged scale, of the bearing taken along the line 4-4 of Fig. 3, and Fig. 5 is a detailed view in cross-section of the ball raceway.

The condenser illustrated is of the triple section type and is mounted within a casing 1 having three compartments which are separated from one another by partitions 2 and 3. The front wall of the casing is denoted by 4 and the rear wall by 5. The partitions within the casing have all of them a central bore through which passes a shaft 6 having rigidly mounted on it slideable condenser halves 7, 8 and 9. A motion of the shaft 6 in axial direction consequently results in a similar displacement of the condenser halves 7, 8 and 9. Stationary condenser halves 12, 13 and 14 are mounted on two supporting rods 10 and 11 of which only the rod 10 is visible in Fig. 1. The rods 10 and 11 are stationary, the movable condenser halves 7, 8 and 9 are provided with bushes 15, 16 and 17 which are slideable on the supporting rod 10 and with similar bushes (not shown) which are movable with respect to the supporting rod 11. These bushes prevent at the same time the shaft 6 from being rotated. The fixed condenser halves 12, 13 and 14 are formed in such manner that the shaft 6 can be moved with respect thereto without any objection.

At its left-hand end the shaft 6 is clamped in a bush 18 provided with a screw thread 19 in which a ball 20 can be displaced. This ball protrudes through an aperture 21' provided in the actuating knob 21 and is pressed into the groove 19 with the aid of an annular blade spring 20'. Owing to the bevelled shape of the walls of the groove 19 and to the pressure exerted by the spring 20' the ball 20 has no play in the groove 19. The actuating knob 21, which has the shape of a hollow bush or shaft, is journalled in a ball bearing 24 in the front plate 4 of the condenser. The actuating knob 21 can only be turned with respect to the condenser casing, owing to the presence of the ball bearing 24, and cannot be displaced in axial direction. A rotatory motion of this knob brings about a displacement of the ball 20 in the groove 19 with the result that the shaft 6 is axially displaced and that each of the movable condenser halves is displaced with respect to the corresponding fixed halves, the alteration of the capacity being thus effected. During this

rotatory motion of the knob 21 the bush 18 and therefore the shaft 6 are displaced with respect to the knob 21.

For the sake of simplicity the journalled shaft 21 is represented in Figure 3 as a hollow bush. In this shaft is provided an annular groove 22 whose walls are formed by conical surfaces 22a and 22b and a bottom portion 22c. The front wall 4 of the casing of the condenser has secured to it a rigid ring 23 which is formed with a conical contact surface 23'. Furthermore the front wall 4 has secured to it, by means of resilient washers 25, another rigid ring 26 which is provided on the inside with a conical contact surface 27. Between the surfaces 22a, 22b, 23' and 27 are clamped three balls 28 which are kept spaced apart by a ball race 29 which has to that end recesses 30. The attachment of the rings 23 and 26 to the front plate 4 of the condenser is effected by means of stud bolts 31. With this construction the contact surface 27 is the movable one. Owing to the resiliency of the washers 25 it is permanently pressed against the balls 28. Although the balls are spaced apart by a distance corresponding to an angle at the centre of 120°. Figures 1 and 3 show for the sake of clearness two balls.

A displacement of the shaft 21 to the right (see the direction of the arrow A in Fig. 3) is excluded owing to the fact that the ring 23 is rigid and is immovably secured to the wall 4. If the shaft 1 would be displaced, due to an overload, in the direction of the arrow B, the resilient washers 25 ensure, jointly with the ring 26, that, after this overload has ceased to exist, the shaft returns again to its original position. In the case of a radial overload on the shaft 21, for example in the direction of the arrow C, the points with which each of the balls is in contact with one of the contact surfaces are displaced in such manner that the circle of contact with one of the contact surfaces merges into a conic section whose plane is no longer perpendicular to the center-line of the shaft 21. The balls have consequently left their position of equilibrium and when the overload C ceases to exist they will return, owing to the action of the resilient washers 25 and to the conical shape of the contact surfaces, to their position of equilibrium, which results in that the shaft is automatically restored to its original position, the shaft being consequently self-centering. Also during this displacement the ring 26 and therefore the contact surface 27 have first left their position of equilibrium and then returned into this position.

It appears from Fig. 5 that it is advantageous that the angles formed by the surfaces 22a and 22b on the one hand and the surfaces 23' and 27 on the other hand with respect to the axis X-Y of the ball and therefore with respect to the center-line of the journalled shaft are mutually equal two by two. The generating lines of the surfaces 22a, 22b form an angle a with the axis of revolution X-Y of each ball whereas the surfaces 23' and 27 each form an angle b with the axis X-Y. It is thus ensured that the distance of the point of contact of each of the balls with the surface 22a, 22b from the axis X-Y acquires the same value c whereas for the surfaces 23' and 27 this distance has a value d , slip of the shaft being thus avoided.

From the above it will be clear that the journaling according to Figs. 3 and 4 may be utilised with great advantage in the condenser described with reference to Figs. 1 and 2 for supporting

the shaft or bush 21. Any radial or axial over-load of the knob 21 with the aid of which the condenser is adjusted, consequently has, after this overload has ceased to exist, no influence on the position of the movable portion of the condenser with respect to the fixed portion thereof since the shaft 21 is self-centering. Any play is suppressed since owing to the fact that the balls are pressed by resiliency, any play is absorbed in the bearing 24; neither has the ball 20 any play in its path.

What I claim is:

1. In a tuning condenser provided with an end plate and a rotor shaft, a bearing for journaling the shaft in said end plate whereby it is capable of being self-centered and not subject to play, said bearing comprising a hollow sleeve provided with a race-way on its outer surface, the rotor shaft extending into said hollow sleeve and adapted to be actuated thereby, a pair of annular disk members, one of which has its outer periphery rigidly mounted on the end plate, means for resiliently mounting the other disk member at

its outer periphery, the inner peripheral portions of said disk members being formed to provide conical contact surfaces, balls provided in the sleeve race-way and cooperating with the disk contact surfaces, and a retaining member for the 5 balls.

2. In a tuning condenser provided with an end plate and a control shaft, a hollow sleeve serving as a control member for the control shaft provided with a race-way on its outer surface, the 10 control shaft extending into said hollow sleeve, means for laterally moving the control shaft upon rotation of the hollow sleeve control member, a pair of annular disk members, one of which has its outer periphery rigidly mounted on the end 15 plate, means for resiliently mounting the other disk member at its outer periphery, the inner peripheral portions of said disk members being formed to provide conical contact surfaces, balls provided in the sleeve race-way and cooperating 20 with the disk contact surfaces, and a retaining member for the balls.

ALEXANDRE HOROWITZ.
